DINNER PLATE OR SIMILAR ARTICLE

Charles H. McKaig, Camillus, N.Y., assignor to Syracuse China Corporation, Syracuse, N.Y., a corporation of New York

Filed Jan. 4, 1967, Ser. No. 5,309

Term of patent 14 years

(Cl. D44—15)

The figure is a top plan view of a dinner plate of conventional configuration showing my new design, it being understood that the ornamentation shown in full lines is continuous about the entire periphery in the path indicated by broken lines.

I claim:

The ornamental design for a dinner plate or similar article, as shown and described.
